COMBINATION FRONT PANEL UNIT AND BUMPER FOR A MOTOR HOME

Marvin E. Nerem, Forest City, Iowa 50436

Continuation of abandoned design application Ser. No. 25,509, Oct. 15, 1970. This application Oct. 12, 1971, Ser. No. 188,637

Term of patent 14 years

Int. Cl. D12—10

U.S. Cl. D14—6 S

FIG. 3

FIG. 1

FIG. 2

FIG. 1 is a front elevational view of a combination front panel unit and bumper for a motor home embodying my new design;

FIG. 2 is a left side elevational view thereof; and

FIG. 3 is a right side elevational view thereof.

This is a continuation of application Ser. No. D. 25,509, filed Oct. 15, 1970, now abandoned.

I claim:

The ornamental design for a combination front panel unit and bumper for a motor home, substantially as shown.
